US00D970375S

(12) **United States Design Patent** (10) **Patent No.:** **US D970,375 S**
(45) **Date of Patent:** **** Nov. 22, 2022**

(54) **CASE FOR ELECTRONIC DEVICE**

(71) Applicant: **ELAGO COMPANY CO., LTD.**,
Goyang-si (KR)

(72) Inventor: **Chanwoo Lee**, Goyang-si (KR)

(73) Assignee: **ELAGO COMPANY CO., LTD.**,
Goyang-si (KR)

(**) Term: **15 Years**

(21) Appl. No.: **29/813,821**

(22) Filed: **Nov. 1, 2021**

(51) LOC (13) Cl. **10-06**

(52) U.S. Cl.

USPC **D10/118.2**; D10/121

(57) **CLAIM**

The ornamental design for a case for electronic device, as shown and described.

DESCRIPTION

FIG. 1 is a front, top and right side perspective view of a case for electronic device showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, top, and left side perspective view thereof;

FIG. 9 is a front, top and right side exploded perspective view thereof in use, in which the case is separated from an electronic device; and,

FIG. 10 is a front, bottom and right side perspective view thereof in use, in which the case is attached to the electronic device.

The broken lines shown in FIGS. 9 and 10 depict environment and form no part of the claimed design.

1 Claim, 7 Drawing Sheets
